(57) **CLAIM**

The ornamental design for a camera flash, as shown and described.

DESCRIPTION

FIG. 1 is a top front perspective view of a camera flash;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another front view thereof, in which the camera flash is combined with a digital camera;

FIG. 9 is a bottom front perspective view thereof, in which the camera flash is combined with a digital camera;

FIG. 10 is another top front perspective view thereof, in which a flashing portion is protruded from a main body and rotated horizontally by 90 degrees

FIG. 11 is another top front perspective view thereof, in which a flashing portion is rotated longitudinally by 90 degrees from the position in FIG. 10; and,

FIG. 12 is another top front perspective view thereof, in which a flashing portion is rotated longitudinally by 90 degrees from the position in FIG. 11.

The broken lines shown in the drawings are directed to environment and are for illustrative purpose only; the broken lines form no part of the claimed design.
